UNITED STATES PATENT OFFICE.

HENRY K. ATWELL, OF SYRACUSE, NEW YORK.

TROUSERS FOR ATHLETES.

Application filed March 6, 1926. Serial No. 92,705.

The object of this invention is to provide a pair of trousers particularly designed for use by foot-ball players, the waist portion of which is adapted to be variably contracted, without the use of a separate belt, and without being wrinkled or puckered, and is so constructed that it may be widely opened, to permit its application to a separately formed hip pad, previously placed on the hips and back of the wearer, and its contraction on the pad to securely confine the latter in its predetermined position, without liability of displacement, so that the pad may be securely confined, not only when the wearer stands erect, but also when he is in a stooping or crouching position.

I attain this object by the improved construction hereinafter described and claimed.

Of the accompanying drawings forming a part of this specification,—

Figure 1 is a perspective view, looking toward the front, and showing a pair of trousers embodying the invention, the waist portion being in a loose condition.

Figure 2 is a view similar to the upper portion of Figure 1, looking toward the back.

Figure 3 is a perspective view, looking toward the front, and showing the straps shown by Figures 1 and 2, withdrawn from their guides.

Figure 4 is a section on line 4—4 of Figure 3.

Figure 5 is a section on line 5—5 of Figure 2.

The same reference characters indicate the same parts in all of the figures.

The front of the trunk or body portion of the trousers, from which the legs 12 depend, is provided with the usual vertical opening 13, and with means for closing or contracting the same. Said means may include eyelets 14, and a lacing (not shown) engaged with the eyelets. The body front is provided at opposite sides of the opening with front strap guides, which in this instance, include vertical slits 15 and 15^a, and vertical loops or cross strips 16 and 16^a.

The body back includes a transverse lower portion, extending continuously across the back, said portion being that below the dotted line $\alpha\alpha$ (Figure 2) and comprising, in this instance, portions 17, 17 of the body fabric, and a gore 18 interposed between the portions 17. The body back includes also side portions 19, 19, integral with and pro-

jecting upwardly from the portions 17, to the upper edge of the back, and united to each other by a connection 20, formed in any suitable manner. The side portions 19 separately overlap each other at the midlength of the back, above the connection 20, as shown by Figure 4, and are provided with rear strap guides 21, 21^a and 21^b, formed as vertical slits.

Joined to and preferably integral with one of the side portions 19, is an elongated strap 22. An elongated strap 23 is joined to and is preferably integral with the other side portion 19. Said straps constitute extensions of, and extend in opposite directions from, the side portions 19, and pass through the rear strap guides, and the front strap guides. The straps are adapted to meet at the front of the body, as shown by Figure 1, and are provided with means whereby they may be adjustably connected, said means being preferably embodied in a tongue buckle 25, on the outer end of the strap 23, and holes 26 in the strap 22.

When the straps are disconnected, the waist portion may be widely opened and then drawn upward onto the usual or any suitable separately formed hip pad (not shown) previously applied to the wearer's body. The straps may then be connected and tensioned to any desired extent, to contract the waist portion and securely confine the hip pad.

The overlapping side portions 19 of the back and the inner portions of the straps are caused to slide on each other, by the operation of tensioning the straps, so that the back of the waist portion is telescopic, and adapted to be contracted without wrinkling or puckering. A hip pad contacting with said telescopic back is, therefore, firmly and smoothly confined against the corresponding portions of the wearer's body, and is free from liability to be displaced by strains caused by body contortions.

It will be seen that the inner portion of the strap 22, and the part of the side portion 19 with which it is joined, are located within the inner portion of the strap 23, and the corresponding part of the other side portion. It is essential that the straps meet at the outer side of the body front, so that the inner strap 22 must pass through a slit in the body, in order that its outer end may lie on the outer surface of the body front. This is permitted, so far as the strap

22 is concerned, by the front slit 15, through which the outer portion of the strap 22 passes. The rear slits 21 through which the inner portion of the strap 22 passes, serve to 5 guide and confine or prevent edgewise movements of the inner portion of the strap. Any other suitable guiding and confining means may be substituted for the rear slits 21.

- 10 As shown, the strap 23 extends through the slit 21 in the other overlapping rear and side member and outward through the slit 15^a in the front of the body, while the strap 22 passes successively through the slits 21^a, 15^b, 21^b, in the back and side portion, and the slit 15 in the front portion. By this arrangement, both of the strap portions include sections which are exposed within the waist band of the garment, in position to engage 20 with the body of the wearer over the hips and by drawing the ends of the straps together, said waist band will be caused to be uniformly compressed about the wearer's waist, and securely retain in position a previously applied hip pad.

It is obvious that the improved trousers may be used by players of any athletic games.

I claim:

- 30 1. Trousers of the character described, including leg and body sections, the front of the body being separated into two members by a vertical opening extending through its upper edge and provided on opposite sides of said opening with slits closed at both ends, the back and sides of the body including a lower portion continuous throughout the width of the garment and an upper portion constituting the waist portion of the 35 garment which is divided to provide two 40

overlapping members that extend to the upper edge of the back and the free edges of which terminate in strap-like parts that extend through the aforesaid slits in the front of the body portion, each of said strap-like 45 portions having an exposed section within the waist portion of the garment, above the hip portion whereby it is adapted to engage the body of the wearer over the hips.

2. Trousers of the character described, including leg and body sections, the front of the body being separated into two members by a vertical opening extending through its upper edge and provided on opposite sides of said opening with slits closed at both 50 ends, the back and sides of the body including a lower portion continuous throughout the width of the garment and an upper portion which constitutes the waist portion of the garment and is divided to provide two 55 overlapping members that extend to the upper edge of the back and the free edges of which terminate in strap-like parts, one of said overlapping members having a slit 23 formed therein and the other of said members having two slits 21^a, 21^b, formed therein, the strap-like extension of one of the overlapping sections extending through the slit 23 and one of the aforesaid slits in the 60 front of the body and the other said strap-like extension extending through the slits 21^a, 21^b, and the other slit in the front of the body, whereby each of said straps includes an exposed section within the waist 65 portion of the garment above the hip portion thereof for the purpose described.

In testimony whereof I have affixed my signature.

HENRY K. ATWELL.
